CRIBBAGE BOARD

Leroy L. Colon, Elmwood Park, Ill.

Application October 11, 1947, Serial No. 779,347

6 Claims. (Cl. 235—90)

1

This invention pertains to a novel cribbage board or like game counting device wherein a tally of the score of two or more players is kept by advancing pegs bodily along a predetermined pegging course.

An objectionable feature which is characteristic of conventional cribbage counting devices resides in the fact that the players are likely to become confused as to the correct position of their pegs as the pegging progresses along the course of 120 holes employed in the game of cribbage. This arises from the fact that in conventional boards the course is subdivided into two rows of 30 holes each, requiring that each row be pegged twice for a complete game. Consequently, there is a likelihood of a player's mistaking the number of times he has pegged a row, or the direction of pegging, or of becoming confused in some other manner. I am aware that efforts have been made to evolve a counting device which eliminates these objections; however, to my knowledge, all such devices not only fail to accomplish their object but in many cases are additionally objectionable by reason of being relatively expensive, complicated or impractical in other respects.

It is an object of the present invention to provide a simple, inexpensive cribbage counter board or device wherein the course of pegging holes for each of two or more players is arranged in a single, continuous series, enabling each player to peg uninterruptedly from the beginning to the end of the course without repetition or reversal of the series of pegging operations.

Another object is to provide a device of the foregoing type wherein the aforesaid series or rows of pegging holes are each arranged in a continuous, unidirectional, upwardly spiraling path along a continuous, progressively rising and spirally contering track or land, terminating at the uppermost point of the structure in a single finish hole, wherein the winning player deposits his final peg.

More specifically, it is an object of this invention to provide a simple and inexpensive pegging device which is well suited to molding from a suitable plastic or like material, said device being contoured to afford a continuous, upwardly and inwardly spiraling track, way or land provided with parallel, similarly spiraling rows of pegging holes subdivided into groups of five, the

2

arrangement being such that a pegging course is pursued in a given single direction along said track until the entire series of 120 holes has been finally pegged out at a substantially central and elevated point or station provided with a single winning peg hole.

Yet another object is to provide a device of the foregoing nature which is well adapted by its upwardly spiraling, generally conical shape to be fabricated in a hollow sectional outline for the internal reception of playing cards, pegs and the like.

In the drawings,

Fig. 1 is a perspective view illustrating a cribbage board or counter device fabricated in accordance with the principal of the present invention, showing the device in position for pegging, with players pegs inserted in the holes thereof;

Fig. 2 is a bottom perspective view illustrating the hollow interior of the device shown in Fig. 1; and

Fig. 3 is a view in vertical transverse section on a line generally corresponding to the line 3—3 of Fig. 1.

Referring to Figs. 1 and 3, the cribbage board or counter device of the present invention is generally designated by the reference numeral 10. It may be cast from metal, fabricated of wood or readily molded from any of a large variety of suitable well-known plastic compositions available on the market in many attractive colors. The device is of a generally circular external outline and is molded to provide a spiral track, way or land 11 of uniform width. This track commences at a point on one external or peripheral and lower side of the device and spirals uniformly inwardly and upwardly in a counterclockwise direction, from a starting point denoted 12 to a finish point 13, at which the track terminates in a raised dome-like contour. The continual but gradual upward rise of the spiraling track 11 results in a uniformly upwardly and radially inwardly stepped spacing of opposed portions of the track when the device is viewed in section, as in Fig. 3.

At the starting point 12 the track 11 is provided with radially spaced pairs of aligned storage holes 14 wherein the two pegs 18 employed by each player may be received at or prior to commencement of pegging. Parallel spiraling

rows of pegging holes 15 succeed and are aligned with the storage holes 14, the holes 15 progressing counterclockwise upwardly in conformity with the shape of the track 11. In accordance with conventional cribbage board practice, the two rows of parallel pegging holes are each subdivided into 24 groups of five. In use, pegging is continued by the players, starting at 12, until the winning score is made, whereupon the winning player deposits his final peg in the single winning hole 16 at the central finish point 13 at the top of the device. This completes the game.

For the purpose of accommodating a deck of playing cards, designated by the reference numeral 17, and pegs 18, the device of the invention preferably is molded in a hollow outline, affording a space 19 of substantial volume in its interior for the reception of these or other articles. If desired, a releasable cover may also be provided for this cavity in a manner which will suggest itself.

In using the foregoing counting device, the players, in progressing their pegs spirally upwardly, each along his individual row of pegging holes, are enabled to tell at a glance who is ahead and by exactly how much. It is unnecessary for each player to keep in mind how many passes have been made by himself or his opponent over a pegging course, or their direction. Moreover, during the progress of the game a definite, invisible goal is afforded, in the form of the winning hole 16 at the peak or apex of the board, thereby furthering a competitive interest in the game. Obviously, more than two rows of spiraling pegging holes may be provided in the track, thereby accommodating more players, without in any way adding to the complexity of the device or its use.

The present counter is simple, attractive of appearance and inexpensively produced. It definitely eliminates the sources of the arguments which inevitably and continually spring up in the use of standard known counting devices.

I claim:

1. A cribbage counter device comprising a one-piece structure having a substantially continuous track surface spiraling radially and vertically between laterally and vertically spaced starting and finish zones, and rows of pegging holes on said surface extending in longitudinally spaced succession therealong.

2. A cribbage counter device comprising a one-piece structure having a substantially continuous track surface spiraling radially and vertically between laterally and vertically spaced starting

5 and finish zones, rows of pegging holes on said surface extending in longitudinally spaced succession therealong, and a single winning hole in said finish zone for the reception of the final peg of the winning player.

3. A cribbage counter device comprising a one-piece structure of generally circular outline having a substantially continuous track surface spiraling radially inwardly and upwardly from a 10 starting point to a finish zone, and parallel rows of pegging holes on said surface arranged in longitudinally spaced succession therealong.

4. A cribbage counter device comprising a one-piece structure of generally circular outline having a substantially continuous track surface spiraling radially inwardly and upwardly from a starting point to a finish zone, parallel rows of pegging holes on said surface arranged in longitudinally spaced succession therealong, and a 20 single winning hole in said finish zone for the reception of the final peg of the winning player.

5. A cribbage counter device comprising a one-piece structure of hollow, generally circular, stepped conical outline having a continuous track surface spiraling radially and vertically between radially and vertically spaced starting and finish points, and parallel spiraling rows of longitudinally spaced pegging holes on said surface.

30 6. A cribbage counter device comprising a one-piece structure of hollow, generally circular, stepped conical outline having a continuous track surface spiraling radially and vertically between radially and vertically spaced starting and finish points, and parallel spiraling rows of longitudinally spaced pegging holes on said surface, the 35 interior of said structure being hollow to afford a storage space of substantial size.
